Primary Examiner — Eric Goodman*Assistant Examiner* — Amy Wierenga(74) *Attorney, Agent, or Firm* — Alan D. Kamrath; Kamrath IP Lawfirm, P.A.(57) **CLAIM**

The ornamental design for paper tissue, as shown and described.

DESCRIPTION

FIG. 1 is a top plan view of a paper tissue showing my design; FIG. 2 is a top perspective view thereof;

FIG. 3 is a bottom plan view thereof;

FIG. 4 is a front elevational view thereof; and,

FIG. 5 is a top perspective view of a paper tissue shown in use at the top of a stack of paper tissues depicted in broken line. The broken lines in the drawing depict environmental subject matter only and form no part of the claimed design.
